UNITED STATES PATENT OFFICE.

CHARLES E. EVANS, OF WEED, CALIFORNIA.

METHOD AND APPARATUS FOR RAFTING LOGS.

1,132,767.

Specification of Letters Patent. Patented Mar. 23, 1915.

Application filed November 9, 1914. Serial No. 870,948.

To all whom it may concern:

Be it known that I, CHARLES E. EVANS, a citizen of the United States, residing at Weed, in the county of Siskiyou and State 5 of California, have invented a certain new and useful Improvement in Methods and Apparatus for Rafting Logs, of which the following is a full, clear, concise, and exact description, reference being had to the accompanying drawings, forming a part of 10 this specification.

My invention relates to improvements in logging rafts and in the method of constructing such rafts.

15 One object of my invention is to provide a raft of this character, the logs of which are securely held in bundles or groups, and arranged conveniently for towing.

Another object is to provide an improved 20 method of assembling and arranging the logs whereby the raft may be quickly and conveniently formed.

Other objects will be apparent without specific enumeration thereof.

25 In the accompanying drawings, I have shown two embodiments of the invention which will serve to illustrate the advantages thereof. Other embodiments may be devised, and accordingly I do not necessarily 30 limit myself to those discussed in detail herein.

Figure 1 is a plan view of one of the units of which the raft is composed, certain parts being omitted to simplify the drawing. Fig. 2 is an elevation of a single 35 bundle of logs illustrating the first step of their assembly. Figs. 3 and 4 are similar views illustrating successive later steps in the assembly thereof. Fig. 5 is a central 40 longitudinal section through a completed bundle. Fig. 6 is a section on the line 6-6 of Fig. 4. Fig. 7 is a central longitudinal section of a modified bundle. Fig. 8 is a section on the line 8-8 of Fig. 7. Fig. 9 is an enlarged section on the line 9-9 of Fig. 1. Fig. 10 is a section on the line 45 10-10 of Fig. 9. Fig. 11 is an elevation of the details shown in Fig. 9.

In constructing the raft, the first step is 50 to form the logs into groups, or what may be termed bundles, each consisting of a comparatively small number of logs 1 arranged substantially concentrically about a core 2. The latter may consist of a short length of 55 log of large diameter, preferably larger than the diameter of the logs arranged

about said core, although this is not essential. The logs are arranged preferably with their large ends at one end of the bundle and their small ends at the other. The core 60 2 is arranged near said large ends, as shown in Fig. 2. The initial step in constructing the bundle consists in arranging the logs and core about as shown in Fig. 2 of the drawings, and binding the large ends of 65 said logs with a chain or cable 3, the small ends diverging more or less. These diverging ends are then drawn together and fastened in compact form. This may be accomplished by encircling said ends with a 70 cable or chain 4, one end of which is fastened to a suitable support 5; the other end of which is drawn forward by any suitable source of power, for example a donkey engine. As the small ends of the logs are 75 thus forced together, the slack is taken out of the chain 3 at the other end and the chain put under considerable tension, the individual logs being bent somewhat or sprung about the core 2 as shown more particularly in Fig. 5. The small ends are then 80 held together either by the same chain used to draw them together, or by a further chain 6 as shown in Fig. 4. Both chains 3 and 6 are thereby put under tension by the logs, 85 which tend to fly apart but are very firmly held in a compact bundle. The end chains 3 and 6 are held together by a further chain 7 (which may be a continuation of one of 90 said end chains) the free end of said chain being attached to a cable 8 at the point 9. A plurality of such cables are arranged substantially parallel, as shown in Fig. 1 with the bundles secured in pairs one on each side thereof, said bundles being arranged with 95 their large ends in the direction in which the raft is to be towed, shown by the arrow in Fig. 1. The cables 8 are secured at opposite ends to long spars or logs 10-10, the latter having towing lines 11 connected 100 thereto and converging at the point 12 as shown in Fig. 1. There are preferably as many towing lines 11 as there are cables 8, the towing line and the corresponding cable being attached to the log 10 at approximately 105 the same point so as to avoid any danger of breaking the latter.

The preferred details whereby the towing lines and cable are secured to the log 10 are shown in Figs. 9, 10 and 11 from which it 110 will be seen that each log is reinforced on opposite sides thereof by a flat, steel bar 13

through which pass I-bolts 14 arranged in pairs, or single bolts with an opening at each end. It is to be understood that each cable 8 has as many pairs of bundles attached thereto as the length of said cable warrants. In Fig. 1 only one complete pair of bundles is illustrated as being attached to each cable, but additional pairs are arranged substantially in alinement, one behind the other, throughout the length of the cable. The entire unit may be about six hundred feet long, for example. The complete raft is made up of any desired number of units attached end to end to each other.

In Figs. 7 and 8 I have illustrated another form of bundle wherein the core instead of being made up of a single short section of log, is made up of a plurality of short sections of logs 15 which latter may be smaller than the average of the logs arranged about said core. The method of constructing the bundle is substantially the same as that which has already been described. One of the important characteristics of the bundles, is that the logs are so disposed with respect to each other, that there is normally a tendency to maintain a clearance between the adjacent ends, which clearance is reduced by the encircling end bands or chains which latter therefore are under continual tension. This result may be obtained in various ways other than with the cores illustrated herein. The arrangement described results in the logs being held very securely for an indefinite length of time, whereby they may be towed great distances if necessary, and under adverse conditions, without further attention.

It is obvious that a raft made in accordance with my invention is not necessarily limited to any particular dimensions or to any particular number of units. In fact, a raft may consist of a single unit or a plurality of units, the latter arrangement being preferred. Accordingly, I desire to cover whatever forms of the invention may be devised which fall within the scope of the appended claims.

Having thus described my invention what I claim as new and desire to secure by Letters Patent of the United States is:

1. A raft comprising a plurality of units arranged one behind the other, each unit consisting of a plurality of cables held in substantially parallel relation, and a plurality of pairs of bundles of logs secured to each cable, said pairs being arranged one behind the other.

2. A logging raft comprising a pair of

transversely arranged logs, a plurality of cables secured to said logs and arranged parallel to each other, towing lines extending from a common point to said logs and secured thereto adjacent to the respective points of attachment of said cables, and bundles of logs secured to said cables and arranged to occupy substantially the entire area represented by said transverse logs and cables.

3. A log bundle comprising a plurality of substantially parallel logs, means for spacing certain of said logs apart intermediate the ends thereof, and binding means at each end of said bundle holding the ends of the individual logs closer together than they would be if unrestrained, whereby certain of said logs are sprung slightly and tend to fly apart, thus maintaining the tension of said binding means and insuring the integrity of the bundle as a whole.

4. A log bundle for rafts consisting of a core, a plurality of logs arranged concentrically about said core and projecting beyond both ends thereof and means for binding the ends of said logs together.

5. A log bundle comprising a plurality of logs arranged side by side in the form of a hollow cylinder, means for binding said logs together at the ends thereof and a core arranged intermediate said ends and large enough to maintain said binding means under considerable tension.

6. A log bundle comprising a core, a plurality of logs arranged concentrically about said core with their large ends together, said core being arranged intermediate the ends of said logs but nearer to the larger ends than to the smaller ends, means for binding said larger ends together in a circle of such size as to cause said smaller ends to tend naturally to diverge and means for binding said smaller ends together to prevent such divergence.

7. A log raft comprising a pair of parallel logs, a metal reinforcing bar arranged along opposite sides of each of said logs, I-bolts passing through said logs and reinforcements and cables secured to said I-bolts and connecting said logs.

In witness whereof, I hereunto subscribe my name this 17th day of October A. D., 1914.

CHARLES E. EVANS.
